UNITED STATES PATENT OFFICE

LEO F. EXLEY, OF JOHNSON CITY, NEW YORK, ASSIGNOR TO ENDICOTT JOHNSON CORPORATION, OF ENDICOTT, NEW YORK, A CORPORATION OF NEW YORK

POLISHING AND CLEANING TOOL

Application filed December 12, 1928. Serial No. 325,563.

This invention is a novel revoluble polishing and cleaning tool for burnishing the heads of rivets, bolts, screws, studs, nails, or other predetermined areas without injuring, 5 marring, or marking the adjacent surfaces; and is especially designed for polishing and cleaning the rivet heads in the shanks of shoe soles which secure the usual arch supporters, or the rivet heads in such shanks which 10 imitate arch supporters; the tool providing quick and effective means for doing such work, while protecting the surface of the leather shank adjacent such rivet heads; but it is to be understood that my invention may 15 be used for any purpose for which it is found applicable.

The arch supporters are usually fastened by means of brass rivets which pass through the shank of the sole, and in finishing the 20 shoe the bottom of the sole is covered with paint or enamel and then polished. Up to the present time, no effective means has been provided for removing from the heads of such rivets or the like the stains, bleaches, or 25 coloring materials with which the entire bottom of the shoe sole has been treated. In the polishing operations heretofore used the paint or enamel was not removed from the heads of the rivets, but in order to make a 30 better looking shoe the enamel or paint was later scraped by hand from the said heads. My invention however provides a tool which will quickly and easily remove the paint or 35 enamel from the heads of the rivets in such arch supporter shoes.

Further objects of the invention are to provide, in a manner as hereinafter set forth, a 40 brush for the purpose referred to, which is simple in its construction and arrangement; and is strong, durable, compact, revoluble, 45 controlled by a spring, compressed air, rubber or other suitable means, thoroughly efficient in its use, readily assembled, and comparatively inexpensive to manufacture.

I will explain the invention with reference 50 to the accompanying drawing which illustrates several practical embodiments thereof to enable others to adopt and use the same; and will summarize in the claims the novel features of construction, and novel combina-

tions of parts, for which protection is desired.

In the drawings;

Fig. 1 is a perspective view showing one form of my polishing tool operating upon the 55 rivet heads of a sole shank.

Fig. 2 is an enlarged section through another form of the tool in position for operation showing the adjacent portion of the sole shank and the rivet head, and also showing 60 the adjacent portion of the electric motor used for rotating the tool.

Fig. 3 shows the brush of Fig. 2 engaging the rivet head.

Fig. 4 shows in section a modified form of 65 the tool.

Fig. 5 shows in elevation another modified form of the tool.

As shown, the tool comprises a rotatable shaft 1 having a reduced threaded extension 1a on its outer end for connecting the 70 axially disposed brush 2, or other polishing or abrading element 7 to the shaft 1, said shaft being rotatably mounted within a tubular body 3 of suitable material, the outer 75 end of which terminates at the reduced portion 1a of said shaft, the body 3 forming a journal bearing for the shaft 1. The inner end of body 3 is enlarged as at 3b, a shoulder 3c being formed between the portion 3b and 80 the major portion of body 3, for the purpose hereinafter described.

Slidably mounted upon the major portion 85 of body 3 is a tubular guard 4 extending beyond the outer end of body 3, the lower end of guard 4 being conically contracted as at 4a to form a nozzle of diameter to suit the head of the rivet R or the like which is to be polished. The inner end of guard 4 is enlarged as at 4b and slidably engages the enlarged portion 3b of body 3, a shoulder 4c being formed by the portions 4 and 4b. Within the portion 4b around body 3 between the shoulders 3c and 4c is a coiled 90 spring 5 normally tending to urge the guard 4 outwardly upon the body 3. The movement of guard 4 upon body 3 is limited by screws 3d passing through slots 4d in the guard 4, and tapped into the body 3.

Brush 2 is housed within the outer end of 100

the guard 4, and the brush (shown in Figs. 2 and 3) preferably has wire bristles and is substantially identical in construction with that shown in my prior Patent No. 1,684,481, issued Sept. 18, 1928, and hence needs no detailed description therein, except to state that the cup shaped head 2a is of substantially same diameter as the adjacent portion of body 3, and is provided with an axially disposed tubular portion 2b which is tapped to engage the treaded portion 1a of shaft 1.

10 The bristles 2 are secured in the cup shaped head 2a in the identical manner as that set forth in my aforesaid patent. The groups of wire bristles 2 converge at their outer ends and are adapted to fill the opening in the outer end 4a of the guard sleeve 4 (Fig. 3) when the guard 4 is shifted inwardly upon the body 3.

15 20 Suitable spacing or adjusting washers 6 may be interposed between the cup shaped head 2a of the brush and the outer end of the major portion of shaft 1 to compensate for material wear on the end of the brush.

25 30 Instead of the wire brush 2, a rod like member 7 (Fig. 4) may be screwed upon the portion 1a of shaft 1, the outer end 7a of the brush being prepared with any of the well-known abrading or buffing materials and adapted to engage the head of the rivet.

If desired, the tool may be attached directly to the end bell of an electric motor M as shown in Fig. 2, instead of to the flexible shaft S shown in Fig. 1. In such arrangement it would be necessary to present the work W to the nozzle 4a of the tool instead of presenting the tool to the work. I do not however wish to limit myself to either of the above constructions for obviously a motor

40 45 E might readily be built into the tool itself, as shown in Fig. 5, making the tool and motor portable and self-contained, in which case the tool could be applied to the work W which under some circumstances might be advantageous.

In operation a rotating motion is applied to the assembled shaft 1 and brush. By placing the work W to be cleaned against the nozzle 4a of the guard 4, and applying a slight pressure, the guard 4 is caused to move inwardly upon the body 3 and the rotating brush 2 or rod is brought into contact with the rivet R or the like to be cleaned.

Upon removing the work, the guard automatically returns to its normal position. The guard 4 effectively prevents the brush 2 or rod 7 from coming in contact with the body of the work W and hence prevents the brush from injuring, marking, or marring same, the brush being confined to the rivet head by the guard 4 while at work.

I claim:

1. A machine for polishing heads of rivets and the like in shoe shanks, etc. comprising 55 a tubular body; a shaft extending through

the body; a polishing member carried by said shaft; a shield enclosing the polishing member and slidably connected with the body and normally projecting beyond the end of said member, said shield having an opening the rim of which lies in one plane and approximately corresponds in size to the head of the rivet to be cleaned; means for yieldably holding the shield normally projected beyond the member, while permitting the shield to retract and allow the member to engage the head of the rivet through the opening; said shield protecting the material adjacent the rivet from abrasion by the polishing member; means for limiting the movement of the shield on the body; and means for rotating the shaft.

2. A machine for polishing heads of rivets and the like in shoe shanks, etc.; comprising a tubular body; a rotatable shaft extending through the body; a polishing member connected with one end of said shaft; a tubular shield enclosing the polishing member and slidably connected with the body and normally projecting beyond the end of said member, said shield having an opening the rim of which lies in one plane and approximately corresponds in size to the head of the rivet to be cleaned; spring means for yieldably holding the shield normally projected beyond the member, while permitting the shield to retract as the brush is engaged with the head of the rivet, the shield protecting the material adjacent the rivet from abrasion by the polishing member; and means for limiting the movement of the shield on the body.

3. A machine for polishing heads of rivets and the like in shoe shanks, etc.; comprising a tubular body; a shaft extending through the body and rotatable therein; a brush connected with one end of said rotatable shaft and rotating therewith; a tubular shield slidably connected with the body and having a tapered lower end enclosing the brush and normally projecting beyond the end of said brush, the rim of the opening in the tapered end of the shield lying in one plane and approximately corresponding in size to the head of the rivet to be cleaned; spring means for yieldably holding the shield normally projected beyond the brush, while permitting the shield to retract and allow the brush to engage the head of the rivet; said shield protecting the material adjacent the rivet from abrasion by the brush; and means for limiting the movement of the shield on the body.
